UNITED STATES PATENT OFFICE.

WILLIAM GRADY, OF CORTLAND, NEW YORK, ASSIGNOR OF ONE-HALF TO
IRVING B. FAIRCHILD.

SPROCKET-WHEEL FOR BICYCLES.

SPECIFICATION forming part of Letters Patent No. 605,819, dated June 14, 1898.

Application filed October 16, 1897. Serial No. 655,395. (No model.)

To all whom it may concern:

Be it known that I, WILLIAM GRADY, a citizen of the United States, residing at Cortland, in the county of Cortland and State of New York, have invented certain new and useful Improvements in Sprocket-Wheels for Bicycles; and I do hereby declare the following to be a full, clear, and exact description of the invention, such as will enable others skilled in the art to which it appertains to make and use the same.

My invention relates to certain new and useful improvements in the sprocket-wheels of bicycles; and it consists, essentially, in providing the peripheral portion or pitch-line of the sprocket-wheel or wheels with a band or strip of felt or other similar material capable of absorbing and retaining a lubricant, the band being suitably perforated or slotted to allow it to be slipped over the teeth or cogs of the wheel, as will be hereinafter more fully described, and particularly set forth in the claims.

The object of the invention is twofold, being to furnish lubricant to the chain and to cause it to run noiseless. This object is attained by means of the device illustrated in the accompanying drawings, in which—

Figure 1 is a side elevation of the sprocket-wheels and chain of a bicycle, showing my improvement applied to the larger wheel; Fig. 2, an enlarged peripheral view of a sprocket-wheel provided with the felt band, and Fig. 3 a perspective view of the band detached.

Referring to the several views, the numeral 1 indicates the larger sprocket-wheel of a bicycle, and 2 the driving-chain thereof.

3 indicates a strip or band, preferably felt, which is provided with a series of apertures 4 equal in number to the number of teeth in the sprocket - wheel. The strip is placed around the periphery or pitch-line of the wheel by forcing the teeth or cogs through

the apertures or holes in the strip and securing the ends together, if desired, although in practice I have not found it necessary to do so, as the pressure of the chain serves to "pad" the strip down and hold it in its encircling position.

Any suitable lubricant may be applied to the band to lubricate the chain sufficiently to prevent it from rust and undue wear. As the band completely covers the periphery of the wheel, surrounding, as it does, each tooth or cog, it will be seen that all noise or rattle of the chain is prevented and its wear to some extent protected. When the band becomes worn and no longer fit for use, it can be readily replaced by a new one.

The invention is simple and can be produced at a comparatively trifling cost. It requires little or no trouble to place it upon the wheel or to remove and replace it by another.

If desired, the smaller sprocket-wheel may be also provided with a similar band; but it has not been found necessary to a successful operation and practice of my invention.

Having thus fully described my invention, what I claim as new, and desire to secure by Letters Patent, is—

1. The combination with a sprocket-wheel and chain of a band of fibrous material encircling the periphery or pitch-line of said wheel and carrying a lubricant.

2. The combination, with a sprocket-wheel and driving-chain, of a band of felt, suitably apertured to fit over the teeth or cogs of the wheel and encircle the periphery of the same, and carrying a lubricant.

In testimony whereof I affix my signature in the presence of two witnesses.

WILLIAM GRADY.

Witnesses:

JOHN W. SUGGETT,
IRVING B. FAIRCHILD.
